COMBINED RECEIVER, AMPLIFIER, SPEAKER, TAPE RECORDER AND MICROPHONE THEREFOR

Henry W. Shaw and Milton N. Lanford, Morrilton, Ark.,
assignors to Sound-Craft Systems, Inc., Morrilton, Ark.

Filed Mar. 7, 1969, Ser. No. 16,122

Term of patent 14 years

Int. Cl. D14—01, 04

U.S. Cl. D26—14

Fig. 3.

Fig. 1.

Fig. 2.

FIG. 1 is a front perspective view of a combined receiver, amplifier, speaker, tape recorder and microphone therefor embodying our new design;

FIG. 2 is a rear perspective view of the apparatus as shown in FIG. 1; and

FIG. 3 is another rear perspective view of the apparatus as shown in FIG. 1 with the rear cover removed.

We claim:

The ornamental design of a combined receiver, amplifier, speaker, tape recorder and microphone therefor, substantially as shown and described.
